UNITED STATES PATENT OFFICE

FREDERICK T. ELLIOTT, OF SOMERVILLE, MASSACHUSETTS

SHOCK ABSORBER

Application filed September 11, 1928. Serial No. 305,261.

This invention relates to shock absorbers for automobiles, the object of the invention being the production of an inexpensive but efficient device of this character which will be double acting and in which an automatic valve in the oscillating shaft will control the entire operation of the device and the movement of the car springs will be retarded gradually during the compression 10 and recoil of said springs.

This object is attained by the mechanism illustrated in the accompanying drawings.

For the purpose of illustrating the invention, one preferred form thereof is illustrated in the drawings, this form having been found to give satisfactory and reliable results, although it is to be understood that the various instrumentalities of which the invention consists can be variously arranged 15 and organized, and the invention is not limited to the precise arrangement and organization of these instrumentalities as herein shown and described except as required by the scope of the appended claims.

25 Of the drawings:

Figure 1 represents an elevation of a shock absorber embodying the principles of the present invention.

Figure 2 represents a transverse section 30 of same on line 2, 2, on Fig. 1.

Figure 3 represents a vertical section on line 3, 3, on Fig. 2 with the movable blade in its normal position.

Figure 4 represents a similar section on 35 line 3, 3, on Fig. 2 showing said blade at the extreme of its movement.

Figure 5 represents a section on line 5, 5, on Fig. 2 with the blade at the extreme of its movement, and

40 Figures 6 and 7 represent details of portions of the oscillating shaft and blade to be hereinafter referred to.

Similar characters indicate like parts 45 throughout the several figures of the drawings.

In the drawings, 10 is a cylindrical casing having a cover 11 secured thereto.

This cover 11 is provided with a hub 12 in which is a bearing 13 for an oscillating 50 shaft 14.

The outer end of the shaft 14 has secured thereto an arm 15, the outer end of which at 16 has pivotally connected thereto one end of an adjustable connector the opposite end of which is pivotally connected at 18 to an arm 19 secured to part 20 of the frame of the automobile.

The casing 10 is provided with ears 21 by which said casing may be secured to the body of the automobile in any well known manner.

The shaft 14 extends through a stuffing box 22 of usual construction.

The end wall of the casing 10 has threaded thereto a stud 23 which is fixed 65 from rotation.

This stud 23 extends across the cylindrical inner chamber 24 formed in the casing 10 and is centrally disposed therein.

The stud 23 is fitted into a socket 25 70 formed in the inner end of the oscillating shaft 14.

In the stud 23 are formed two diametrical passages 26 and 27, the passage 27 having a diameter less than that of the passage 26.

75 The inner end of the shaft 14 extends into a depression 28 formed in the end wall of the casing 10.

Disposed within the chamber 24 is a partition 29 extending from the cylindrical wall 80 of the chamber 24 and contacting at its inner end with the periphery of the oscillating shaft 14.

This oscillating shaft 14 is provided with 85 a radial blade 30, the outer end of which contacts with the cylindrical wall of the chamber 24 and the opposite ends of which contact with the end wall of the casing 10 and the inner face of the cover 11.

The partition 29 and the blade 30 coact 90 to divide the chamber 24 into two compartments.

During the oscillation of the shaft 14 the blade 30 is adapted to move through an 95 angle of about 90 degrees from the position shown in Fig. 3 to the position indicated in Fig. 4.

The partition 29 has an opening 31 extending therethrough normally closed by a 100

threaded plug 32 extending through the cylindrical wall of the casing 10.

By removing this plug 32 the chamber 24 may be filled with any desired liquid, the plug 32 being replaced when the chamber has been filled.

A small hole 33 extends through the oscillating shaft 14 and forms a communication or by-pass between the two compartments of the chamber 24 and is open at all times.

This hole 33 is smaller than the passage 27 which in turn is smaller than the passage 26.

The oscillating shaft 14 is provided with oppositely disposed ports 34 and 35 which are adapted to register with the passages 26 and 27 respectively during the oscillation of said shaft 14.

These ports are triangular and their apexes are oppositely disposed as indicated clearly in Figs. 6 and 7 of the drawings.

The passage 26 has an enlarged chamber 36 in which is disposed a ball 37 and a pin 38 extending across this chamber 36 prevents the displacement of said ball.

The normal position of the blade 30 is as indicated in Fig. 3 but when the car springs are compressed and the body of the car moves downwardly relatively to the frame 20, said blade 30 will be moved in the direction of the arrow *a* on said Fig. 3.

When this blade 30 starts to move in the direction of the arrow *a*, the oppositely disposed ports 34 will be fully opened and the liquid in the right hand compartment of the chamber 24 will flow through the passage 26 causing the ball 37 to be forced against the pin 38.

As the ball 37 is of considerable less diameter than the diameter of the chamber 36 the liquid will freely pass from the right hand compartment to the left hand compartment of said chamber 24.

As the blade 30 continues to move in the direction of the arrow *a*, the ports 34 will be closed gradually owing to the triangular shape of said ports so that when said blade reaches the position indicated in Figs. 4 and 5 of the drawings these ports 34 will be wholly closed.

When the blade 30 starts to move in the direction of the arrow *a* the oppositely disposed ports 35 registering with the passage 27 will be wholly closed, but as the blade continues to move in said direction the ports 35 will be gradually opened until the blade 30 reaches the position indicated in Fig. 5 when said ports 35 will be fully opened permitting free flow of the liquid in the chamber 24 from one compartment to the other.

In the return movement of the blade 30 caused by the recoil of the car springs or in the direction opposite to that indicated by the arrow *a*, the liquid in the left hand compartment will be admitted to the chamber 36 forcing the ball valve 37 to its seat thereby closing the passage 26 and preventing any liquid from flowing through said passage.

It is obvious, therefore, that liquid can pass through the passage 26 in only one direction.

During this reverse movement of the blade 30 the liquid in the left hand compartment must flow into the right hand compartment through the passage 27 which is fully opened at the start of the blade 30 in the reverse direction but which gradually closes until the blade reaches the position indicated in Fig. 3 when said passage 27 is wholly closed.

Owing to the triangular shape of the ports 34, 35 and the gradual closing of the passages 26, 27 during the rotation of shaft 14 all shock is effectually prevented both when the car springs are compressing or when recoiling.

It is self-evident, therefore, that a double acting shock absorber is provided taking up the shock when the body of the vehicle is moving downwardly and gradually retarding its movement in the opposite direction.

It is believed that the operation and many advantages of the invention will be understood without further description.

Having thus described my invention, I claim—

1. The combination of a casing having an inner chamber with a cylindrical wall; an oscillating shaft extending through a wall of said casing and across said chamber; a blade thereon with its sides and ends contacting with the walls of said chamber extending from said shaft to the wall of said chamber; a partition in said chamber coacting with said blade to divide said chamber into two compartments; and a member within said shaft having two passages connecting said compartments and adapted to be opened and closed by the oscillation of said shaft.

2. The combination of a casing having an inner chamber with a cylindrical wall; an oscillating shaft extending through a wall of said casing and across said chamber; a blade thereon with its sides and ends contacting with the walls of said chamber extending from said shaft to the wall of said chamber; a partition in said chamber coacting with said blade to divide the chamber into two compartments; and a member within said shaft having two passages connecting said compartments one of which is adapted to be opened and the other closed when said blade is moved in one direction.

3. The combination of a casing having an inner chamber with a cylindrical wall; an oscillating shaft extending through a wall of said casing and across said chamber; a

blade thereon with its sides and ends contacting with the walls of said chamber; a partition in said chamber coacting with said blade to divide the chamber into two compartments; and a fixed member disposed within said shaft and having two passages connecting said compartments one of which is adapted to be opened gradually and the other closed gradually when said blade is moved in one direction.

4. The combination of a casing having an inner chamber with a cylindrical wall; an oscillating shaft extending through a wall of said casing and across said chamber; a blade thereon with its sides and ends contacting with the walls of said chamber; a partition in said chamber coacting with said blade to divide the chamber into two compartments; a fixed member disposed within said shaft and having two passages connecting said compartments and adapted to be opened and closed by the oscillation of said shaft; and a by-pass in said shaft between said compartments which is always open.

5. The combination of a casing having an inner chamber with a cylindrical wall; an oscillating shaft extending through a wall of said casing and across said chamber; a blade thereon with its sides and ends contacting with the walls of said chamber; a partition in said chamber coacting with said blade to divide the chamber into two compartments; and a fixed cylindrical member fitted to a socket in said shaft and having two passages connecting said compartments one of which is adapted to be opened gradually and the other closed gradually when said blade is moved in one direction while the last mentioned passage is gradually opened and the first mentioned passage is wholly closed when the blade is moved in the opposite direction.

6. The combination of a casing having an inner chamber with a cylindrical wall; an oscillating shaft extending through a wall of said casing and across said chamber; a blade thereon with its sides and ends contacting with the walls of said chamber; a partition in said chamber coacting with said blade to divide the chamber into two compartments; and a member having two passages connecting said compartments and adapted to be opened and closed by the oscillation of said shaft, one passage being larger than the other and adapted to open when the blade is moving in one direction and closed when the blade moves in the opposite direction, the larger passage being associated with means regulating the flow of liquid therethrough.

7. The combination of a casing having an inner chamber with a cylindrical wall; an oscillating shaft extending through a wall of said casing and across said chamber; a blade

thereon with its sides and ends contacting with the walls of said chamber; a partition coacting with said blade to divide the chamber into two compartments; a fixed cylindrical member fitted to a socket in said shaft and having two passages connecting said compartments and adapted to be opened and closed by the oscillation of said shaft; and an automatic valve in one of said passages adapted to permit the free flow of liquid in one direction and prevent its flow in the opposite direction.

8. The combination of a casing having an inner chamber with a cylindrical wall; a centrally disposed stud fixedly secured to an end wall of the casing and extending into said chamber, said stud having two diametrical passages therein; a check valve in one of said passages; an oscillating shaft mounted in a bearing in the other wall of the casing and provided with a socket in its inner end fitted to said stud and having ports therein adapted to register with said passages and gradually close the valved passage and gradually open the other passage when the shaft is moving in one direction; a blade radiating from said shaft and extending to the end and cylindrical walls of said chamber; means for moving said blade; and a partition coacting with said blade to divide the chamber into two compartments.

9. The combination of a casing having an inner chamber with a cylindrical wall; a centrally disposed stud fixedly secured to an end wall of the casing and extending into said chamber, said stud having two diametrical passages therein one of which is enlarged at one end; a ball valve in said enlarged end; means preventing the displacement of said ball; an oscillating shaft mounted in a bearing in the other wall of the casing and provided with a socket in its inner end fitted to said stud and having ports therein adapted to register with said passages and gradually close the valved passage and gradually open the other passage during the movement of said shaft in one direction; a blade radiating from said shaft and extending to the end and cylindrical walls of said chamber; means for moving said blade; and a partition coacting with said blade to divide the chamber into two compartments.

10. The combination of a casing having an inner chamber with a cylindrical wall, a centrally disposed stud fixedly secured to an end wall of the casing and extending into said chamber, said stud having two diametrical passages therein; a check valve in one of said passages; an oscillating shaft mounted in a bearing in the other wall of the casing and provided with a socket in its inner end fitted to said stud and having ports therein adapted to register with said passages and gradually close the valved passage and gradually open the other passage dur-

ing the movement of said shaft in one direction; a blade radiating from said shaft and extending to the end and cylindrical walls of said chamber; a restricted by-pass through said shaft always open; means for moving said blade; and a partition coacting with said blade to divide the chamber into two compartments.

11. The combination of a casing having an inner cylindrical chamber; an oscillating shaft extending through said chamber and one wall of said casing, said shaft having two sets of ports; a radial blade on said shaft extending to the walls of said chamber; a fixed stud extending into a socket in the inner end of said shaft and provided with two diametrical passages adapted to register with said ports; a valve in one of said passages adapted to permit the flow of liquid in one direction only; and a partition coacting with said blade to divide said chamber into two compartments.

12. The combination of a casing having an inner cylindrical chamber; an oscillating shaft extending through said chamber and one wall of said casing, said shaft having two sets of ports; a radial blade on said shaft extending to the walls of said chamber; a fixed stud extending into a socket in the inner end of said shaft and provided with two diametrical passages adapted to register with said ports; a valve in one of said passages adapted to permit the flow of liquid in one direction only; a partition coacting with said blade to divide said chamber into two compartments; and a by-pass through said shaft always communicating with both compartments.

13. The combination of a casing having an inner cylindrical chamber; an oscillating shaft extending through said chamber and one wall of said casing, said shaft having two sets of triangular ports; a radial blade on said shaft extending to the walls of said chamber; a fixed stud extending into a socket in the inner end of said shaft and provided with two diametrical passages adapted to register with said ports; a valve in one of said passages adapted to permit the flow of liquid in one direction only; and a partition coacting with said blade to divide said chamber into two compartments.

14. The combination of a casing having an inner cylindrical chamber; an oscillating shaft extending through said chamber and one wall of said casing, said shaft having two sets of oppositely disposed ports; a radial blade on said shaft extending to the walls of said chamber; a fixed stud extending into a socket in the inner end of said shaft and provided with two diametrical passages adapted to register with said ports; a valve in one of said passages adapted to permit the flow of liquid in one direction

only; and a partition coacting with said blade to divide said chamber into two compartments.

15. The combination of a casing having an inner cylindrical chamber; an oscillating shaft extending through said chamber and one wall of said casing, said shaft having two sets of oppositely disposed triangular ports; a radial blade on said shaft extending to the walls of said chamber; a fixed stud extending into a socket in the inner end of said shaft and provided with two diametrical passages adapted to register with said ports; a valve in one of said passages adapted to permit the flow of liquid in one direction only; and a partition coacting with said blade to divide said chamber into two compartments.

Signed by me at 294 Washington St., Boston, Massachusetts, this 8th day of September, 1928.

FREDERICK T. ELLIOTT.
